VENTILATING SYSTEM

Filed Nov. 6, 1919

UNITED STATES PATENT OFFICE

JAMES BURKE, OF ERIE, PENNSYLVANIA, ASSIGNOR TO BURKE ELECTRIC COMPANY,
A CORPORATION OF PENNSYLVANIA

VENTILATING SYSTEM

Application filed November 6, 1919. Serial No. 336,210.

This invention relates to heating and ventilating systems and particularly to such systems having power driven means for moving the air. The chief object of the invention is to provide a system which will be adaptable to the large variety of conditions met with in practice and will be positive in action and easily controlled.

Another object of the invention is to provide the ventilating means as units easily installed at any point and readily connected to distribute the air currents effectively throughout the space to be ventilated.

A further object of the invention is to provide heating and distributing means such that the system may be readily changed from a heating and ventilating means in cold weather to a cooling and air circulating means in summer.

20 In the accompanying drawings,

Fig. 1 is a vertical side view of a portion of a ventilating system illustrating the invention with parts broken away and in section.

Fig. 2 is a plan view of the same.

25 Fig. 3 is a vertical sectional view on line 3—3 of Fig. 1 and

Fig. 4 is a horizontal sectional view on line 4—4 of Fig. 3.

In the embodiment of the invention illustrated in the drawings, supply piping 5 carries a heating fluid to the header 6 and pipes 7 returning the fluid through header 8 and outlet 9. This heating piping is connected to any suitable source of heating fluid such as steam or hot water and is enclosed in a long casing or pipe like structure 10. Air to be heated may be supplied by air inlet 12 connected to an outside source through suitable screens and filters and provided with adjustable valve means 13 to regulate the supply of air. The casing or pipe 10 is extended beyond the heating pipes and at various points is provided with air distributing and ventilating units 15. Each ventilating unit 15 comprising a pipe length or chamber portion 16 adapted to connect sections of the supply pipe or casing 10 and these units 15 will be of standard construction so that installation of the system will require only the building

45 50 of the supply line with suitable heating means

and the ventilating units 15 will simply be interposed at desired points.

In the ventilating units 15 air is drawn down from the chamber or pipe portion 16 by a centrifugal fan structure 17 having oppositely directed volute outlets 18 of a fan casing 20 fastened to the lower face of the chamber 16. The fan casing is in two parts and the lower part carries a fan motor 21 fastened to the casing by flanged ring 22. The fan wheel 25 driven by the motor is of the centrifugal type with spider 26 and radial blades 27 directing the air outward through discharge passages 18 and drawing it down through the axial passage 28 from the chamber 16.

Air is thus sucked in over heating pipes 7 and blown out in divergent streams in desired directions at each ventilating unit. The inflow of air is readily adjusted according to the temperature of the outside air and the number of ventilating units in operation, and when desirable heated air from the room may be readmitted into the supply as by opening doors 30 at the air entrance. By varying the relative adjustments of valve means 13 and doors 30 a wide range of outside and inside air is possible from an exclusively outside supply to an exclusively inside one.

The system of this invention is also widely adaptable in structure and easily installed. The ventilating units may be marketed as separate standard parts and the remainder of the piping may be built up as desired at the site of the installation. In warm weather when the supply of heat will be shut off the system will still operate to ventilate and renew the air and additional fans 35 may be added at the lower ends of the motor shafts to further stir the air.

While the system has been described in connection with a specific embodiment it is not intended to be confined thereto. It is obvious, for instance, that pipes may be carried in a number of directions from a single source as indicated at 5' and 6' (Fig. 1) and that other modifications may be resorted to within the scope of the appended claims.

I claim:—

1. A ventilating unit for a heating and ventilating system comprising a conduit chamber adapted to form a part of a supply pipe, 5 a fan casing connected thereto, and a fan within said casing for drawing air from said chamber and discharging it into the space to be heated or ventilated, said casing being in two sections, one fastened to said chamber 10 and the other suspended therefrom and carrying the fan and the motor therefor.
2. A ventilating system comprising a series of sections adapted to be suspended from a ceiling, heating means in certain of said 15 sections and a plurality of separate motor driven fans in others of said sections and conduit means connecting said heating and fan sections.
3. A ventilating system comprising a series 20 of sections adapted to be suspended from a ceiling, heating means in certain of said sections and a plurality of separate motor driven fans in others of said sections and conduit means connecting said heating and fan sections and an adjustable air supply for said 25 heating section.
4. An air distributing means for a ventilating system comprising a conduit section adapted to be suspended from a ceiling, 30 a fan casing supported from said conduit section and a fan and motor supported by said fan casing, the shaft of said motor being adapted to carry an auxiliary outer ventilating fan.
